(57) **CLAIM**

The ornamental design for a light-emitting device, as shown and described.

DESCRIPTION

FIG. 1 is a front, right perspective view of a light-emitting device showing our new design;
 FIG. 2 is a front, left perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof; and,
 FIG. 8 is a bottom plan view thereof.

The broken lines illustrate portions of the light-emitting device which form no part of the claimed design.

The dash-dot-dash-dot broken lines are boundary lines and define the bounds of the claimed design. The claimed design extends to the boundary lines but does not include the boundary lines.
